UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

STEREOTYPE-PRINTING-PLATE-MATRIX FEED AND MAGAZINE.

1,259,946.

Specification of Letters Patent. Patented Mar. 19, 1918.

Original application filed January 12, 1910, Serial No. 537,700. Divided and this application filed September 4, 1915. Serial No. 48,983.

To all whom it may concern:

Be it known that I, HENRY A. WISE Wood, a citizen of the United States, residing at New York, in the county of New York and 5 State of New York, have invented a new and useful Stereotype-Printing-Plate-Matrix Feed and Magazine, of which the following is a specification.

This is a division of my application Serial No. 537,700, filed Jan. 12, 1910; patented December 14, 1915, No. 1,164,607.

This invention relates to a machine for casting stereotype printing plates. While some of the features thereof are capable of 15 use generally for that class of machines, yet the invention is illustrated in a form in which it is particularly applicable to the casting of flat plates.

Among the objects of the invention are 20 to provide a new machine adapted automatically to take one matrix at a time from a pile of matrices in a magazine, deliver it in the mold, and discharge the matrix when desired; to provide a new matrix feed adapted to be adjusted so that the matrices can be fed in such a way that any desired number of plates can be cast from each matrix, or a plurality of plates from any matrix or matrices and a different number from the 25 others, or a continuous series of plates from a single matrix to provide a magazine capable of accommodating matrices of different sizes; to provide for delivering the matrices by means of a following matrix or dummy 30 matrix pushing each matrix out of the mold; and to provide an improved matrix. The invention also involves improvements in various details of construction as will appear hereinafter.

Reference is to be had to the accompanying drawings, in which—

Figure 1 is a plan of a flat stereotype plate casting machine constructed in accordance with this invention with part of the mechanism removed;

Fig. 2 is a side elevation of a portion of the machine showing the magazine for holding the matrices in position to be fed into the mold;

Fig. 3 is a plan of the same;

Fig. 4 is an end elevation of the parts shown in Fig. 2 with parts in section;

Fig. 5 is a similar elevation with parts removed to show interior construction;

Fig. 6 is a plan similar to Fig. 3 with parts removed and with a matrix in position;

Fig. 7 is a sectional view on the line 7—7 of Fig. 6;

Fig. 8 is a sectional view like Fig. 7 showing the parts in a different position;

Fig. 9 is an elevation of a portion of the matrix magazine; and

Fig. 10 is a plan of a matrix suitable for use in this machine.

This invention is shown in a form for casting flat stereotype plates and as embodying a frame 30. At one end of the frame is a main transverse shaft 38 which by bevel gears 39 drives a longitudinal shaft 40 at the front side of the machine. On this shaft is a cam 140 driving the pump plunger 145 in the melting pot 146. This supplies metal at intervals to the casting box 93—95. This is operated by a cam 106 on the shaft 40, but the mold operating mechanism is not shown.

At one side of this frame 30 are a pair of laterally projecting brackets 41 separated from each other and on which is supported the magazine for the matrices. This magazine is shown as comprising vertical side members 42 and 43 resting on the brackets 41. Both of these side members are provided with flanges 44 and 45 which extend along the supporting brackets 41. These flanges project inwardly a short distance and serve to guide the corners of the matrices. On the delivery side of the magazine the side members are adjustably held together by means of cross bars 46. One of the side members is firmly secured to its bracket and the other is adjustable thereon. Both of the side members are provided with two slots in which the ends of these cross bars 46 extend and the latter are screwed or otherwise fixed to these side members in the slots and are provided with fastening pieces 47. Each of the cross bars 46 is provided with a longitudinal slot 48 through which pass screws or bolts 49 by which it is secured adjustably to the other side member. In this way, the distance apart of the side members, and therefore, the width and length of the

65

95

100

magazine, can be regulated as desired so as to provide for matrices M of any desired width and length.

Extending along the side of the magazine are a pair of reciprocable rods 50. On each of these rods are mounted two fingers 51 which project toward each other through horizontal slots 52 in the side members of the magazine and are provided at their inner ends with supports 53 in the magazine on which the matrices are supported, as indicated more particularly in Fig. 7. The matrices are dropped by the longitudinal motion of these supports 53 which permits 10 a single matrix to be dropped at a time on a central and two side supports 54. Adjustably mounted on the cross bars are retaining bars 55—55 extending inwardly and spaced from the bottom of the magazine a distance 15 sufficient to permit the matrices to be discharged under them.

The rods 50 are guided in boxes 56 supported by the flanges 44 and 45 and by boxes 57 supported at the other ends of the side 20 members 42 and 43. On each of the rods 50 is a key 58 on which the fingers are adjustable longitudinally. They are held in position by screws 59. The dropping of the matrices one by one is accomplished as follows:—Each matrix is provided with a pair of opposite edge notches M' near one end, and with a pair of similar opposite edge notches M^2 at a greater distance from the other end. These notches are all of a shape 25 and size to permit the supports 53 to pass through them, and are the same distance apart as said supports. The matrices are placed in the magazine alternately, that is, so that notches M' and M^2 are alternately 30 at the head or feeding edge of matrix. When the rods 50 move forward, if the supports register with the notches, the bottom matrix will drop and the next matrix will rest on the support (Fig. 8). Then on 35 the completion of the reverse motion the second matrix will drop.

In order to move the rods 50 the shaft 40 is provided with a gear or pinion 61 which operates a gear 62 on which is mounted a 40 double throw cam 64. Gear 62 rotates on a stud 63. This cam operates a spring-pressed cam roller 65 on a lever 72 which is connected by screw 73 to lever 66 which is provided with a gear segment 67. This gear 45 segment meshes with a pinion 68 and turns the same periodically so as to oscillate a pinion 70 and shaft 69, and reciprocate the pair of rods 50 which are provided with racks on the bottom. This carries the fingers 51 back and forth periodically and uniformly so as to deliver the matrices under them, as has been described. To adjust the throw of the lever 66 to accommodate the location of the notches M' and M^2 a rod 66^a

is pivoted to the lever and has an adjustable 65 collar 66^b which engages the bracket on which the rod is mounted. The lever 66 and therefore the roller 65, is yieldingly held in position by a spring 66^c. The screw 73 can be removed so as to leave the lever 66 free 70 so that no matrices will be fed. Then if the screw 73 is out the lever can be turned to feed a matrix and held for casting any number of plates from it. On the shaft 69 is a handle 71 by which the shaft can be turned 75 independently of the power, and held so as to cast any desired number of plates from a single matrix.

On the shaft 40 is located a cam 75 which operates a spring-pressed forked lever 76. 80 By means of a lever 77 this reciprocates a slide 78 which is mounted on a guide or support 79. This slide carries a pair of ears 80 supporting a rod 81 on which are mounted two hubs 82 each having a pushing finger 85 83 thereon. One of these is adjustable along the rod to provide for matrices of different widths. Every time the roll 65 comes either on the low or high part of the cam 64 the slide 78 is moved to discharge a matrix from 90 the magazine. If it is desired to deliver matrices at alternate rotations of the shaft 40, so as to cast two plates from each matrix the cam 64 is changed. In this case the cam would have one high and one low part of 95 approximately equal length. This slide 78 then moves forwardly and the fingers 83 which come up between the brackets 41 engage the rear of the matrix deposited thereon to push it out of the magazine, as shown 100 more particularly in Fig. 5.

The side member 42 is shown as stationary, and the side member 43 is shown as provided with a projection 85 having slots 86 through which it is adjustably secured 105 by screws 87 to one of the brackets 41. A reciprocating supporting plate 91 is mounted to move in vertical guides 92 on the frame, and carries the lower casting box 93.

The upper casting box 95 is supported on 110 two brackets 320 on which are standards 321 carrying rods 322 and 332. The upper box is supported from the rods by plates 323.

Through the bases of the plates 323 pass thimbles 329 which extend slightly below 115 the bottom thereof. A bolt 330 extends through each thimble and these bolts fasten the upper box to the standards 321. The rod 332 rests in open slots on the brackets 320.

The matrices are discharged from the magazine under the end gages of the casting box and positively moved into register with the side gages by means of the pusher fingers 83.

Then the supporting plate 91 is raised by a cam 106 on the shaft 40 by means not shown.

When the casting boxes close another plate will be cast from the same matrix unless another one or a dummy is fed into the casting box. In that case the old matrix will 5 be forced out of the box by the new matrix guided by the end gages and drop at the rear of the frame.

In operation the matrices are placed in the magazine with the notches M' and M^2 arranged alternately so that as the feeding rods move back and forth, one matrix will be 10 fed down at the end of the forward stroke and the next one at the end of the reverse stroke. When it is desired to operate the machine one or a definite number of times 15 without casting a plate, one or more dummy matrices with their corners cut away are placed in the magazine. Under ordinary conditions a matrix will be fed into the mold 20 under the end gages which hold its edges on the lower casting box. Then the latter rises, lifts the top section a very slight distance and brings the parts into registration with the nozzle 149 ready for the casting of 25 a plate. Then the lower box moves down. The upper box remains substantially in the first position with the cast plate held by the side gages which underlie its edges, as has been stated.

30 It will be seen therefore that one plate can be cast from each matrix, or any desired number, or a plurality of plates can be cast from the first or any particular matrix and a different number from the rest of them, or a 35 continuous series of plates can be cast from a single matrix. It will be seen also that the used matrices are pushed by a succeeding matrix or dummy from the casting box and that the dummy matrices will be delivered in 40 the same way. The various mechanisms are adjustable in all necessary ways to take care of plates of different sizes.

While I have illustrated and described a preferred embodiment of the invention and 45 shown it as applied to the casting of flat printing plates, I am aware that many modifications can be made in the various details of construction and the sequence of operations and that most of the parts can be employed for casting stereotype plates, and in 50 fact other articles, of different shape and character from the plates specified. Therefore, I do not wish to limit myself to the details of construction or sequence of operations or shape of plates described herein 55 but what I do claim is:—

1. The combination with a matrix magazine having slots through its opposite walls, of means extending into the slots for supporting the matrices in the magazine.

2. In a device of the class described, the combination of a magazine for holding matrices having an adjustable wall, and movable means projecting in back of said wall

for supporting the matrices in the magazine. 65

3. In a device of the class described, the combination of a magazine for holding stereotype printing plate matrices having an adjustable wall and an opposite wall, said adjustable wall and the opposite wall having slots therethrough near the bottom, and movable means projecting in through the slots for supporting the matrices in the magazine. 70

4. In a device of the class described, the combination of a magazine for holding matrices having walls having slots therethrough near the bottom, and movable means projecting in through the slots for supporting 80 the matrices in the magazine.

5. In a device of the class described, the combination of a magazine for holding stereotype printing matrices provided with walls having horizontal slots therethrough near the bottom, means supported by said two walls and projecting in through the slots for supporting the matrices in the magazine, and means for moving said supporting means to permit the matrices to be dropped 90 from the bottom of the pile in the magazine one by one.

6. In a device of the class described, the combination of a magazine for holding matrices having walls, means supported by said 95 walls and projecting in between them for engaging and supporting the matrices in the magazine, and means for reciprocating said matrix supporting means whereby when they register with notches in the edges of the 100 matrices the latter will fall.

7. In a device of the character described, the combination of a magazine for matrices, a plurality of fingers projecting into the bottom of said magazine and adapted to support 105 the edges of the matrices therein, and a pile of matrices in the magazine resting on said fingers each matrix having notches in its edges adapted to receive said fingers, whereby when the fingers are moved into registration with the notches a matrix will drop past 110 the fingers.

8. In a device of the character described, the combination of a magazine for matrices, a plurality of fingers projecting into said magazine and adapted to support the edges of the matrices therein, a pile of matrices in the magazine resting on said fingers, each matrix having notches in its edges adapted 115 to receive said fingers, the notches being located nearer one end of each matrix than the other and the matrices being arranged alternately with respect to the position of said notches whereby when one matrix is dropped, the next one will be supported by 120 the fingers until they move.

9. In a device of the character described, the combination of a matrix magazine, a rod

mounted on the same, fingers on the rod projecting below the edges of the matrices in the magazine and supporting them, and means for reciprocating said rod.

5 10. In a device of the character described, the combination of a matrix magazine, a reciprocable rod, fingers on the rod projecting below the edges of the matrices in the magazine, and means for adjusting the fingers on 10 the rod.

11. In a device of the character described, the combination of a matrix magazine, two parallel rods on opposite sides thereof each having fingers thereon projecting under the 15 matrices in the magazine, and means for simultaneously reciprocating the said rods to deposit the matrices.

12. In a device of the character described, the combination of a matrix magazine, 20 fingers projecting under the matrices in the magazine, means for simultaneously moving said fingers, means under the magazine for receiving the matrices deposited from the magazine, and a pusher adapted to engage the matrices dropped from the magazine and push them from under it.

13. In a device of the character described, the combination of a shaft, a matrix magazine, fingers projecting under the matrices 30 therein, means connected with said shaft for reciprocating said fingers to bring said fingers into a position in which they will no longer support the bottom matrix so that the same will drop, a slide mounted to move 35 under the magazine, and means operated by said shaft for moving said slide to push a matrix out.

14. In a device of the character described, the combination of a shaft, a matrix magazine, 40 fingers projecting into the magazine for supporting matrices therein, means connected with said shaft for reciprocating said fingers a plurality of times during each revolution of the shaft to bring said fingers 45 into a position in which they will no longer support the bottom matrix so that the same will drop, a slide mounted to move under the magazine, means operated from said

shaft for moving said slide back and forth and pushing matrices out of the magazine, 50 and a casting box located adjacent to the delivery side of the magazine in position for receiving a matrix discharged therefrom.

15. In a machine of the character described, the combination of a magazine for holding stereotype plate matrices, means for feeding said matrices out of the magazine, comprising a pivoted lever, an arm pivoted 55 on the same axis, means for swinging the arm periodically, and a detachable connection between the arm and lever, whereby when the connection is detached, the lever 60 will not be operated.

16. A magazine for stereotype printing plate matrices, comprising a fixed side wall, 65 an opposite wall adjustable toward and from the fixed wall, and end members for engaging the corners of the matrices.

17. A magazine for stereotype printing plate matrices, comprising a fixed vertical 70 wall, a movable wall and horizontal bars at the end, the movable wall being adjustable along said bars toward and from the fixed wall.

18. A magazine for stereotype printing plate matrices, comprising a fixed vertical 75 wall, an opposite vertical wall adjustable toward and from the fixed wall, and movable means at the bottom of the magazine for supporting the matrices.

19. As an article of manufacture, a matrix 80 having two notches of substantially the same shape located in the same margin outside the bolster, but at different distances from the center.

20. As an article of manufacture, a stereotype printing plate matrix having a pair 85 of opposite notches in its edges near one end, and a pair of opposite notches of substantially the same shape in its edges at a different distance from the other end, said notches all being located entirely outside the bolster.

In testimony whereof I have hereunto set my hand.

HENRY A. WISE WOOD.
